ROTARY PUMP

Floyd M. Kirkpatrick, Erie, Pa., assignor to General Electric Company, a corporation of New York

Application November 26, 1949, Serial No. 129,644

20 Claims. (Cl. 230—137)

1

My invention relates to pumps and more particularly to pumps of the rotary type.

It is an object of my invention to provide an improved pump having parts symmetrically arranged to give a minimum dynamic unbalance.

It is another object of my invention to provide a pump including an improved arrangement for minimizing surges.

Further objects and advantages of my invention will become apparent as the following description proceeds and the features of novelty which characterize my invention will be pointed out with particularity in the claims annexed to and forming part of this specification.

In carrying out the objects of my invention a rotor having a spherical surface is arranged for rotation within a housing having a complementary spherical surface. The rotor is provided with two intersecting grooves each of which has a piston segment positioned therein. The piston segments are prevented from rotating with the rotor, but are permitted to oscillate laterally. These segments are arranged so that each blocks one of the grooves while the other effects compression of the fluid within the groove against the blocking segment.

For a better understanding of my invention reference may be had to the accompanying drawings in which Fig. 1 is a view partly broken away of a refrigerating unit including a compressor embodying my invention; Fig. 2 is an enlarged plan view, partly broken away, of the compressor shown in Fig. 1; Fig. 3 is an enlarged end view partly in section of the compressor shown in Fig. 1; Fig. 4 is an exploded view of the compressor; Figs. 5 through 12 are views of the rotor and parts associated therewith in different positions of the rotor; Figs. 13 through 20 show developed views of the rotor and its associated parts in positions of the rotor corresponding to those shown in Figs. 5 through 12, respectively; Fig. 21 is a sectional view of a modified assembly arrangement; Fig. 22 is an end view of the assembly shown in Fig. 21; Fig. 23 is a plan view, partially broken away, of a modified form of my invention; and Fig. 24 is a partial view taken along the lines 24—24 in Fig. 23.

In the following description the pump is described in connection with its application as a compressor in a refrigerating apparatus but it will be apparent that it may be utilized in many other applications where pumping of fluid is required. Referring now to Fig. 1, there is shown a hermetically sealed case 1 within which is mounted a compressor 2. The compressor is positioned within the housing by rings 3 and 4 which fit within grooves in the case 1 and engage opposite faces of the compressor 2. The compressor is driven in any suitable manner as by an electric motor (not shown) incorporated within the

2

case 1 and connected to the compressor through a drive shaft 5. Compressed refrigerant is discharged from the compressor through conduits 6 and 7 into a common conduit 3 from which it is circulated through the refrigerating system (not shown). Vaporized refrigerant is returned from the refrigerating system through a conduit 9 which discharges the refrigerant into the interior of the case 1. Vaporized refrigerant within the case 1 is taken into the compressor through inlet conduits 10 and 11, the open ends of which are positioned above the level 12 of any liquid refrigerant or oil within the case 1.

Referring now to Figs. 2, 3, and 4 it can be seen that the compressor is driven through the shaft 5 which is supported within a bearing 13. The compressor includes a housing 14 which is composed of two complementary parts 15 and 16. The inner surface of each of the housing parts 15 and 16 is curved, as indicated at 17 and 18, respectively so that when the two parts are assembled a spherical surface, forming a spherical chamber, is provided within the interior of the housing. In the form shown the housing parts are of such width that the ends of the sphere formed by the inner surfaces thereof are truncated. However, if desired, a housing could be enlarged and the inner surfaces of the parts 15 and 16 continued to provide a substantially complete sphere. The housing parts 15 and 16 are held in sealing engagement by devices such as screws 19 which pass through bores 20 in the upper housing part 15 and are arranged in threaded engagement with threaded openings 21 in the housing part 16.

A rotor 22 is provided within the housing, the rotor being driven by the shaft 5. The outer surface of this rotor is curved to provide a generally spherical surface having the same radius of curvature as the inner surface of the housing so as to rotate smoothly in engagement therewith. In the form shown the rotor is truncated, providing flat faces 23 and 24, and oscillation of the axis of rotation of the rotor is resisted by an arcuate ring 25 which fits within a groove 26 in the housing and engages the face 24 of the rotor. However, it will be apparent that, if desired, the rotor could be made in the form of a substantially complete sphere or ball instead of the truncated form shown. The bearing 13 may, if desired, be formed in two halves each integral with one of the two parts of the housing 14. Since the bearing 13 maintains the axis of rotation of the rotor fixed, the arcuate ring 25 may be omitted, if desired.

The rotor is provided with two circumferential grooves 27 and 28. These grooves intersect each other at diametrically opposite points of the rotor, one such intersection being indicated at 29. These grooves are inclined at equal angles with

respect to a plane perpendicular to the axis of the rotation of the rotor and extending through the two points of intersection of the grooves 27 and 28. In order to effect pumping of fluid a piston segment 30 is positioned within the groove 27 and a similar piston segment 31 is positioned within the groove 28. The outer spherical surfaces 30a and 31a of the piston segments 30 and 31 respectively are in line with the spherical surface of the rotor 22 and hence are in engagement with the spherical surface of the housing 14. Each of these piston segments is in the form of a semi-circular or half-annular section extending on a great circle of the rotor 22 substantially half the circumference thereof. To effect pumping of fluid by the compressor it is necessary to restrain the piston segments 30 and 31 against rotation with the rotor while still permitting lateral oscillation of these segments during such rotation of the rotor. This is accomplished by providing a pin or projection on each of the piston segments pivotally engaging a block which is slidably positioned within a transverse slot or recess in the housing 14. Thus, the piston segment 30 includes a cylindrical projection or pin 32 which pivotally engages a sliding block 32'. The block 32' is slidably positioned within a recess 33 formed in the housing part 15 adjacent the rotor 22, the sliding block 32' being substantially the same width as the width of the recess 33. A similar projection or pin 34 is provided on the piston segment 31 and this pin 34 pivotally engages a sliding block 34'. The sliding block 34' is positioned in a recess 35 formed in the lower housing part 15 adjacent the rotor 22 and the width of the block 34' is substantially the same as the width of the recess 35. To facilitate oscillation of the piston segments the bottoms of the grooves 27 and 28 are formed as part of the surface of a sphere concentric with the surface of the rotor 22, as indicated at 27' and 28', respectively, and the adjacent faces of the piston segments are formed with the same curvature as the bottoms of the grooves 27 and 28.

Two additional transverse recesses 36 and 37 are provided in the housing 14 adjacent the rotor 22. Each of the transverse recesses 33, 35, 36, and 37 is provided for conducting fluid either to or from the interior of the compressor, and for this purpose each of the recesses is of sufficient length to extend in communication with one or the other of the grooves 27, 28 at the point where the groove is the greatest distance from the perpendicular plane through the intersections of the grooves, for example, as indicated at 38. The recesses 36 and 37 are connected through passages 39 and 40, respectively, in communication with the inlet conduits 11 and 10, respectively. Conversely, the recesses 33 and 35 are connected through passages 41 and 42, respectively, in the housing in communication with the discharge conduits 6 and 7, respectively.

The construction and operation of the compressor can be understood more clearly by referring to Figs. 5 through 12, which show the positions of the various parts associated with the rotor in different successive positions of the rotor, and to the corresponding development views shown in Figs. 13 through 20, respectively. The successive positions shown in Figs. 5 through 12 and Figs. 13 through 20 differ by a 45° rotation of the rotor 22. For convenience in description, the transverse recesses 33 and 36 have been superimposed in dotted lines in Figs. 5 through 12, inclusive, and transverse recesses 33, 35, 36

and 37 have been similarly indicated in Figs. 13 through 20, inclusive. The direction of rotation of the rotor 22 is indicated by the arrows. Starting with Fig. 5, wherein the rotor occupies a position corresponding to the position shown in Fig. 2, Figs. 5 through 12, inclusive, show the position of the various associated parts at 45° intervals throughout one revolution of the rotor. A 45° rotation of the rotor 22 from the crossover position of the piston segments 30, 31 shown in Fig. 5 to the position shown in Fig. 6 causes a lateral shifting of the piston segments and also a rotational movement of the rotor 22 relative to the piston segments since the segments are restrained against rotation by the pins 32, 34 and blocks 32' and 34'. An additional 45° turn of the rotor causes a shifting of the parts to the position shown in Fig. 7. A feature of my invention is that each of the piston segments 30, 31 simultaneously effects a pumping of fluid from the groove in which it is positioned and blocks the other groove at one of the intersections so as to act as a barrier against which the other piston segment effects compression of fluid. Further, the blocking segment divides the blocked groove into two portions, into one of which fluid is taken and from the other of which fluid is discharged during the relative movement of the segments caused by rotation of the rotor. This can be seen by referring, for example, to Fig. 7 wherein the piston segment 30 blocks the groove 28 as shown at 43 and the piston segment 31 blocks the groove 27 as indicated at 44. During the movement from the position shown in Fig. 6 to that shown in Fig. 7 the distance between an end 45 of the piston segment 30 and the blocking face or side 44 of the piston segment 31 increases and fluid is therefore drawn into this portion of the groove 27 through the inlet conduit 11, the inlet passage 39 and the recess 36. Simultaneously, the groove 28 has moved relative to the piston segment 31 which is positioned within the groove 28 so that the length of the groove 28 between an end 46 of the piston segment 31 and the blocking face or side 43 of the piston segment 30 is decreasing, thereby resulting in a compression of fluid in this portion of the groove 28 and discharge of the fluid through the recess 33, the exhaust passage 41, and the conduit 6. This action continues progressively through the position shown in Fig. 8 until the piston segments 30 and 31 reach the crossover point shown in Fig. 9. At this point the exhausting of the fluid by the piston segment 31 from the groove 28 against the blocking face 43 of the piston segment 30 has been completed. Similarly, the intake of fluid into the groove 27 between the end 45 of the piston segment 30 and the blocking face 44 of the piston segment 31 has been completed.

It will be noted that the transverse inlet recess 36 in the housing is spaced from the transverse discharge recess 33 by a distance indicated at 47. Similarly, the diametrically opposite pair of inlet and discharge recesses 37 and 35, respectively, are circumferentially spaced from each other by an amount indicated at 48 in Fig. 3. The ends of the piston segments 30, 31 are positioned adjacent the spaces 47, 48 and move transversely within the area encompassed by the spaces 47, 48. Thus, the ends 45, 46 of the piston segments 30, 31, respectively, move laterally adjacent the space 47. Similarly, the opposite end 49 of the piston segment 30 and the opposite end 50 of the piston segment 31 move adjacent

the space 48 between inlet recess 37 and discharge recess 35. It can be seen, therefore, that the ends of the piston segments project beyond the transverse passages into the area therebetween and the piston segments thus block communication between the spaced inlet and discharge recesses except for a small amount at the exact point of crossover illustrated in Figs. 2, 5, and 9. The arranging of the ends of the piston segments so that each extends beyond a transverse recess into the area between adjacent transverse inlet and discharge recesses also blocks communication between the grooves 27 and 28 through the recesses. Thus, referring to Fig. 7, for example, the piston segment 30 overlaps transverse recess 33 and its end 45 projects into the space 47. Communication from recess 33 is, therefore, limited to the groove 28 and communication between the recess 33 and the groove 27 and between the grooves 27 and 28 through the recess 33 is blocked by the end portion of the piston segment 30. Similarly, communication between transverse recess 36 and groove 28 is blocked by the overlapping end 46 of the piston segment 31 which extends beyond the recess 36 and into the space 47 between recesses 33 and 36, and communication between the grooves 27, 28 through the recess 36 is also blocked. Communication from the recess 36 is therefore limited to the groove 27.

The adjacent ends of the piston segments 30, 31 are shaped so that these ends are enabled to pass closely adjacent each other at both the crossover points shown in Figs. 2 and 5 and the opposite crossover point illustrated in Fig. 9. Referring, for example, to the end 45 of the piston segment 30 it can be seen that this end is shaped to provide two inclined surfaces 51, 52 meeting at an apex 53. The inclined surface 51 makes an angle with a side or face 54 of the piston segment 30 which deviates from a right angle by an amount equal to the angle which each of the grooves 27, 28 makes with a plane extending through the intersection 29 of the concentric grooves 27, 28 and also through the diametrically opposite intersection of these grooves perpendicular to the axis of the rotor. The inclined surface 52 makes the same angle with the opposite side or face 43 of the piston segment 30. The adjacent end 46 of the piston segment 31 similarly includes inclined surfaces 55 and 56 meeting at an apex 57. These surfaces make the same angle with sides or faces 58 and 44, respectively, of the piston segment 31 as the inclined surfaces 51 and 52 do with the sides 54 and 43, respectively, of the piston segment 30. The opposite ends of the piston segments 30, 31 are shaped in the same manner. As best illustrated in the crossover positions shown in Figs. 2, 5, and 9 this particular shape of the ends of the piston segments enables the piston segments 30, 31 to move laterally past each other at both the crossover points with the ends positioned closely adjacent each other. Thus, at the crossover point shown in Figs. 2 and 5 the inclined surfaces 51 and 56 of the ends of the piston segments 30 and 31, respectively, are substantially parallel to each other and are thereby enabled to move past each other while still positioned closely adjacent each other. Similarly, in the opposite crossover position shown in Fig. 9 the inclined surfaces 52 and 55 of the piston segments 30 and 31, respectively, are disposed substantially parallel to each other and are similarly enabled to move past each other while still

being maintained closely adjacent each other. In order to minimize leakage at the crossover points shown in Figs. 2, 5, and 9, a check valve 8a is placed in the discharge conduit 8, as shown in Fig. 1. To further reduce leakage two such valves may be employed closer to the compressor, one in each of the discharge conduits 6 and 7.

From the crossover position shown in Fig. 9 the various parts assume, at successive 45° intervals in the rotation of the rotor, the positions shown in Figs. 10, 11, and 12. An additional 45° rotation of the rotor beyond the position shown in Fig. 12 returns the parts to the original position shown in Figs. 2 and 5. Referring to Figs. 10, 11, and 12, it can be seen that the portion of the groove 27 between the end 45 of the piston segment 30 and the blocking face or side 58 of the piston segment 31 gradually increases, vaporized refrigerant thereby being drawn into this increasing space from the case through the inlet conduit 11, the passage 39, and the transverse inlet recess 36. Similarly, the space between the end 46 of the piston segment 31 and the blocking face or side 54 of the piston segment 30 progressively decreases in size, compression of the vaporized refrigerant within the space between the end 46 of the piston segment 31 and the blocking face 54 being effected. This compressed refrigerant is discharged through the transverse discharge recess 33, the passage 41, and the conduits 6 and 8. When the rotor has moved to the point where the parts are in positions as shown in Figs. 2 and 5 the length of the groove 27 between the end 45 of the piston segment 30 and the blocking face 58 of the piston segment 31 has reached a maximum, completing the intake of fluid to the groove 27, and the compressing and discharging of refrigerant from the groove 28 between the end 46 of the piston segment 31 and the blocking face 54 of the piston segment 30 has also been completed.

The representations in Fig. 2 and in Figs. 5 through 12, inclusive, illustrate the movement of the rotor and of the piston segments with reference to one transverse inlet recess and one transverse discharge recess. As illustrated in Fig. 3, the compressor includes two diametrically opposite inlet recesses 36 and 37 and two diametrically opposite discharge recesses 33 and 35. It will be apparent, therefore, that while the movement of the rotor is effecting an intake of fluid through the passage associated with the recess 36 and a discharge of fluid through the passage associated with the recess 33, a simultaneous intake and discharge is being effected at the opposite side of the rotor through the recesses 37 and 35, respectively. In order to illustrate the overall operation more clearly, the developed views shown in Figs. 13 through 20, inclusive, have been included. These views correspond to those shown in Figs. 5 through 12, inclusive; thus, in Fig. 13 the parts are shown in the same relative positions as in Fig. 5, in Fig. 14 in the same relative position as in Fig. 6, and in Fig. 15 in the same relative positions as in Fig. 7, etc. The same numerals have been applied to corresponding parts in these two groups of figures. For convenience, each developed view has been illustrated directly below the corresponding view of the group embracing Figs. 5 through 12, inclusive. To illustrate the operation more clearly the transverse inlet recesses 36 and 37 and the transverse discharge recesses 33 and 35 have been superimposed in dotted lines in the developed views shown in Figs. 13 through 20, inclusive.

Referring to Fig. 13 it will be noted that the ends of the piston segments are both at the crossover point. It can be seen further by reference to this figure that the groove 27 is in communication with the transverse inlet recess 36 and with the transverse discharge recess 35. The groove 28 is in communication with the transverse inlet recess 37 and the transverse discharge recess 33. Referring now to Fig. 14 wherein the rotor has moved 45 degrees in the direction indicated by the arrow, it can be seen that the groove 27 is divided by the piston segment 31 into two parts 59 and 60, the portion 59 of the groove 27 being in communication with the inlet recess 36 and the portion 60 of the groove 27 being in communication with the discharge recess 35. At the same time the piston segment 30 divides the groove 28 into two portions 61 and 62, the portion 61 of the groove 28 being in communication with the discharge recess 33 and the portion 62 of the groove 28 being in communication with the inlet recess 37. Thus, the motion of the rotor in moving from the position shown in Fig. 13 to the position shown in Fig. 14 has effected the simultaneous intake of fluid through conduit 11, passage 39, and the recess 36 to the portion 59 of the groove 27 and the discharge of compressed fluid from the portion 60 of the groove 27 through the exhaust recess 35 and thence through passage 42 and conduits 7 and 8. At the same time fluid is taken into the portion 62 of the groove 28 through the conduit 10, passage 40 and inlet recess 37, and fluid is discharged from the portion 61 of the groove 28 through the discharge recess 33 and thence through passage 41 and conduits 6 and 8.

The progressive action can be followed further by a comparison of the positions of various parts in Figs. 14, 15, and 16. By this comparison it can be seen that the portion 59 of the groove 27 becomes progressively larger effecting a continuing intake of fluid while the portion 60 of the groove 27 becomes progressively smaller continuing the discharge of fluid through the discharge recess 35. Simultaneously the portion 62 of the groove 28 progressively enlarges continuing to receive fluid therein and the portion 61 decreases thereby causing a further discharge of fluid from the portion 61 of the groove 28 through the discharge recess 33.

A comparison of Figs. 14, 15, and 16 illustrates that the discharge of the fluid from the portion 61 of the groove 28 is effected by relative movement between the end 46 of the piston segment 31 and the blocking face 43 of the piston segment 30 which blocks the groove 27 at one intersection 63 of the grooves 27 and 28. Similarly, the discharge of the fluid from the portion 60 of the groove 27 is effected by relative movement of an end 64 of the piston segment 30 and blocking face 58 of the piston segment 31 at the intersection 29 of the grooves 27 and 28. The intersections 29 and 63 of the grooves 27 and 28 are at diametrically opposite points of the rotor 22. Similarly, the progressively enlarging portion 59 of the groove 27 is blocked at one end by the end 45 of the piston segment 30 and at the other end by the face 44 of the piston segment 31, relative movement of the blocking face 44 of the piston segment 31 and the end 45 of the piston segment 30 resulting in a progressive increase in the size of the portion 59 during this period of rotation of the rotor. The progressively enlarging portion 62 of the groove 28 is

blocked at one end by an end 65 of the piston segment 31 and at the other end by the face 54 of the piston segment 30, relative movement of the blocking face 54 of the piston segment 30 and the end 65 of the piston segment 31 resulting in a progressive increase in the size of the portion 62 during this period of rotation of the rotor. When the crossover position illustrated in Fig. 17 is reached, the portion 59 of the groove 27 and the portion 62 of the groove 28 have reached their maximum size, completing the intake of fluid into these portions of the grooves. Similarly, the exhausting of fluid from the portion 60 of the groove 27 and the portion 61 of the groove 28 has been completed.

Movement of the rotor beyond the point illustrated in Fig. 17 initiates a compression and discharge of the fluid which during the previous half revolution of the rotor has been taken into the portion 59 of the groove 27 and the portion 62 of the groove 28. This action is illustrated progressively in Figs. 18, 19, and 20. Referring to these figures it can be seen that the movement of the rotor through the successive 45 degree position illustrated effects a progressive reduction in the size of the portion 62 of the groove 28 through the relative movement of the blocking face 54 of the piston segment 30 and the end 46 of the piston segment 31. This effects a discharge of fluid through the discharge recess 33. Similarly, the rotation of the rotor effects a reduction in the size of the portion 59 of the groove 27 through the relative movement of the blocking face 44 of the piston segment 31 and the end 64 of the piston segment 30, causing a discharge of fluid through the discharge recess 35.

At the same time the portion 60 of the groove 27 and the portion 61 of the groove 28 which, during the preceding half revolution of the rotor progressively decreased to effect discharge of fluid through discharge recesses 35 and 33, respectively, now progressively enlarge, causing an intake of fluid into these portions of the grooves 27 and 28 through inlet recesses 36 and 37, respectively. The enlarging of the portion 60 of the groove 27 is effected by the relative movement between blocking face 58 of the piston segment 31 and the end 45 of the piston segment 30. Similarly, a progressive enlarging of the portion 61 of the groove 28 is effected by the relative movement between the blocking face 43 of the piston segment 30 and the end 65 of the piston segment 31. The fluid taken into the portion 60 of the groove 27 and the portion 61 of the groove 28 during the half revolution of the rotor illustrated in Figs. 18, 19, and 20 is compressed and discharged therefrom during the half revolution of the rotor illustrated in Figs. 14, 15, and 16.

It will be apparent, therefore, that the intake and discharge of fluid from each of the grooves occurs twice per revolution of the rotor, fluid being taken into one portion of the groove and simultaneously discharged from another portion of the groove during each half revolution of the rotor. There are, therefore, four compression pulses per revolution of the rotor and the distribution of the compressing effect into four such pulses reduces the surge considerably below that in a reciprocating compressor, for example, having only one compression pulse per revolution. Moreover, the construction described provides a smooth acceleration and deceleration of the seg-

ments 30 and 31 which act both as pistons and as valves.

In Figs. 21 and 22 there is shown a modified arrangement for assembling the parts of the pump. This modified form includes a housing composed of two parts 66 and 67 which cooperate to provide a generally spherical chamber 68 for receiving the spherical rotor (not shown). In this form, in lieu of employing devices such as the screws 19 for holding the two parts of the housing in assembled position, the parts 66 and 67, corresponding to the parts 15 and 16, respectively, of the form previously described, are snugly received within a hollow cylindrical housing 69. The cylindrical housing 69 includes a shoulder 70 which spaces the rotor from the face 71 of one end of the housing. An opening 72 is provided in this end of the housing 69 and affords a bearing surface 73 for the driving shaft (not shown). The bearing surface 73 maintains the driving shaft and the rotor in proper alignment within the chamber 68. A resilient arcuate ring 74, adapted to be received within a groove 75, is employed for maintaining the parts 66 and 67 in assembled relationship against the shoulder 70. A recess 76 is provided in the housing part 66 and a pin 77 mounted in the cylindrical housing 69 projects into the recess to prevent rotation of the housing formed by parts 66 and 67. The overall assembly illustrated in Figs. 21 and 22 may be assembled within a case similar to the case shown in Fig. 1.

In Figs. 23 and 24 there is illustrated a modified form of my invention utilizing a different arrangement for permitting oscillation or lateral movement of the piston segments and at the same time preventing rotation of the piston segments with the rotor. The same numerals have been used to designate corresponding parts in Figs. 23 and 24 and in the preceding figures. As in the form shown in Figs. 2, 3, and 4, the modification illustrated in Figs. 23 and 24 includes a two-part housing having an upper part 78 and a lower part 79, corresponding to the parts 15 and 16 respectively. Arcuate grooves are provided in the face of housing part 78, one such groove being indicated at 80 in Fig. 24, and complementary arcuate grooves are provided in the abutting face of the lower housing part 79, one such groove being indicated at 81 in Fig. 24. In the assembled position of the parts 78, 79 these grooves cooperate to form diametrically opposite recesses adjacent the surface of the rotor 22, one such recess being indicated at 82 in Fig. 24. An arcuate segment or key 83 is positioned in the recess 82 and a corresponding arcuate segment or key 84 is positioned in the diametrically opposite recess. The recesses permit oscillation of the keys 83, 84 laterally of the rotor but prevent rotation of the keys with the rotor. In order to prevent rotation of piston segments 30' and 31' with the rotor while at the same time permitting oscillation of these piston segments, the piston segments 30', 31' are pivotally connected to the keys 83, 84 by pins 85 and 86, respectively. During rotation of the rotor each of the keys 83, 84 is free to move laterally in its respective recess, thus permitting oscillation of the piston segments 30', 31'. The necessary pivoting of the piston segments 30', 31' is permitted by the pivotal connection between these piston segments and the keys 83, 84 provided by the pins 85, 86.

Operation of the modified form shown in Figs. 23 and 24 with respect to the pumping of fluid

is the same as that of the form shown in Figs. 1, 2, 3, and 4, and the detailed description and analysis of the operation set forth in discussing Figs. 5 through 20, inclusive, is equally applicable to the modified form illustrated in Figs. 23 and 24.

While I have shown and described specific embodiments of my invention, I do not desire my invention to be limited to the particular constructions shown and described, and I intend by the appended claims to cover all modifications within the spirit and scope of my invention.

What I claim as new and desire to secure by Letters Patent of the United States, is:

- 15 1. A pump comprising a housing having a spherical chamber therein, a rotor within said chamber, said rotor having a spherical surface arranged to engage the surface of said chamber, said rotor having a pair of circumferential grooves formed in said spherical surface thereof, said grooves intersecting each other at two diametrically opposite points, a semicircular piston segment positioned in each of said grooves, means for maintaining said piston segments against rotation with said rotor while permitting lateral oscillation of said segments, and an inlet recess and a discharge recess within said housing adjacent said spherical surface of said rotor communicating with each of said grooves, both of said recesses extending transversely with respect to said grooves, said recesses being circumferentially spaced from each other and being disposed on opposite sides of a plane extending between the ends of said segments and along the axis of said rotor.

- 20 2. A pump comprising a housing having a spherical chamber therein, a rotor within said chamber, said rotor having a spherical surface arranged to contact the surface of said chamber, said rotor having a pair of circumferential grooves formed in said spherical surface thereof, said grooves intersecting each other at two diametrically opposite points, a semicircular piston segment positioned in each of said grooves, an inlet recess and a discharge recess within said housing adjacent said spherical surface of said rotor communicating with each of said grooves, both of said recesses extending transversely with respect to said grooves, said recesses being circumferentially spaced from each other and being disposed on opposite sides of the plane extending between the ends of said segments and along the axis of said rotor, and means engaging said housing and said piston segments for maintaining said piston segments against rotation with said rotor and permitting lateral oscillation of said piston segments.

- 25 3. A pump comprising a housing having a spherical chamber therein, a rotor within said chamber, said rotor having a spherical surface arranged to engage the surface of said chamber, said rotor having a pair of circumferential grooves formed in said spherical surface thereof, said grooves intersecting each other at two diametrically opposite points, a semicircular piston segment positioned in each of said grooves, means for maintaining said piston segments against rotation with said rotor while permitting lateral oscillation of said segments, an inlet recess within said housing communicating with one of said grooves, a diametrically opposite inlet recess within said housing communicating with the other of said grooves, a discharge recess within said housing adjacent said spherical surface of said rotor communicating with said one of said

grooves, and a diametrically opposite discharge recess within said housing communicating with said other of said grooves, all of said recesses extending transversely with respect to said grooves, each of said inlet recesses being circumferentially spaced from the corresponding one of said discharge recesses and being disposed on the opposite side from said corresponding one of said discharge recesses with respect to a plane extending between the ends of said segments and along the axis of said rotor.

4. A pump comprising a housing having a spherical chamber therein, a rotor within said chamber, said rotor having a spherical surface arranged to engage the surface of said chamber, said rotor having a pair of circumferential grooves formed in said spherical surface thereof, said grooves intersecting each other at two diametrically opposite points, a semicircular piston segment positioned in each of said grooves, means for maintaining said piston segments against rotation, said segments being arranged for lateral oscillation during rotation of said rotor, an inlet recess and a discharge recess within said housing adjacent said spherical surface of said rotor communicating with each of said grooves, both of said recesses extending transversely with respect to said grooves, said recesses being circumferentially spaced from each other and being disposed on opposite sides of a plane extending between the ends of said segments and along the axis of said rotor, the piston segment in one of said grooves extending across said other of said grooves at one intersection of said grooves to block flow of fluid along said other of said grooves, the piston segment in said other of said grooves extending across said one of said grooves at the other intersection of said grooves to block flow of fluid along said one of said grooves.

5. A pump comprising a housing having a spherical chamber therein, a rotor within said chamber, said rotor having a spherical surface arranged to contact the surface of said chamber, said rotor having a pair of circumferential grooves formed in said spherical surface thereof, said grooves intersecting each other at two diametrically opposite points, a semicircular piston segment positioned in each of said grooves, an inlet recess within said housing adjacent said spherical surface of said rotor communicating with one of said grooves, a discharge recess within said housing adjacent said spherical surface of said rotor and spaced circumferentially from said inlet recess and communicating with the other of said grooves, both of said recesses extending transversely with respect to said grooves, and means for maintaining said piston segments against rotation with said rotor while permitting lateral oscillation of said segments, said means maintaining the adjacent ends of said piston segments in the area between said inlet recess and said discharge recess.

6. A pump comprising a housing having a spherical chamber therein, a rotor within said chamber, said rotor having a spherical surface arranged to contact the surface of said chamber, said rotor having a pair of circumferential grooves formed in said spherical surface thereof, said grooves intersecting each other at two diametrically opposite points, a semicircular piston segment positioned in each of said grooves, two diametrically opposite inlet recesses within said housing adjacent said spherical surface of said rotor, two diametrically opposite discharge recesses within said housing adjacent said spherical

surface of said rotor, all of said recesses extending transversely with respect to said grooves, one of said inlet recesses and one of said discharge recesses communicating with each of said grooves, each of said discharge recesses being circumferentially spaced from a corresponding one of said inlet recesses, means engaging one of said piston segments and extending into one of said recesses for maintaining said one of said piston segments against rotation with said rotor while permitting lateral oscillation of said one of said piston segments, and means engaging the other of said piston segments and extending into another of said recesses for maintaining said other of said piston segments against rotation with said rotor while permitting lateral oscillation of said other of said piston segments, the adjacent ends of said piston segments being maintained by said last two means in the area between corresponding spaced inlet and discharge recesses.

7. A pump comprising a housing having a spherical chamber therein, a rotor within said chamber, said rotor having a spherical surface arranged to contact the surface of said chamber, said rotor having a pair of circumferential grooves formed in said spherical surface thereof, said grooves intersecting each other at two diametrically opposite points, a semicircular piston segment positioned in each of said grooves, two diametrically opposite inlet recesses within said housing adjacent said spherical surface of said rotor, two diametrically opposite discharge recesses within said housing adjacent said spherical surface of said rotor, all of said recesses extending transversely with respect to said grooves, one of said inlet recesses and one of said discharge recesses communicating with each of said grooves, each of said discharge recesses being circumferentially spaced from a corresponding one of said inlet recesses, a block slidably disposed in one of said transverse recesses, a pin for pivotally connecting one of said piston segments and said block for maintaining said one of said piston segments against rotation with said rotor while permitting lateral oscillation of said one of said piston segments, a second block slidably disposed in another of said recesses, and a second pin pivotally connecting the other of said piston segments and said second block for maintaining said other of said piston segments against rotation with said rotor while permitting lateral oscillation of said other of said piston segments, the adjacent ends of said piston segments being maintained by said last two means in the area between corresponding spaced inlet and discharge recesses.

8. A pump comprising a housing having a spherical chamber therein, a rotor within said chamber, said rotor having a spherical surface arranged to contact the surface of said chamber, said rotor having a pair of circumferential grooves formed in said spherical surface thereof, said grooves intersecting each other at two diametrically opposite points and making equal angles with a plane extending along the axis of rotation of said rotor, a semicircular piston segment positioned in each of said grooves, each of said piston segments including two parallel elongated side walls, two diametrically opposite inlet recesses within said housing adjacent said spherical surface of said rotor, two diametrically opposite discharge recesses within said housing adjacent said spherical surface of said rotor, all of said recesses extending transversely with respect

to said grooves, one of said inlet recesses and one of said discharge recesses communicating with each of said grooves, each of said discharge recesses being circumferentially spaced from a corresponding one of said inlet recesses, and means for maintaining said piston segments against rotation with said rotor and for maintaining the adjacent ends of said piston segments in the area between corresponding spaced inlet and discharge recesses, the ends of said piston segments being formed of two inclined surfaces meeting at a central apex, said inclined surfaces making the same angle with said parallel side walls of said piston segments as the grooves make with the plane extending through the axis of rotation of said rotor whereby as the ends of said piston segments move past each other during lateral movement in either direction the adjacent inclined surfaces of said piston segments are in substantially parallel relationship making possible a minimum clearance between the ends of said piston segments.

9. A pump comprising a housing having a spherical chamber therein, a rotor within said chamber, said rotor having a spherical surface arranged to engage the surface of said chamber, said rotor having a pair of circumferential grooves formed in said spherical surface of said rotor, said grooves intersecting each other at two diametrically opposite points, a first semicircular piston segment in one of said grooves, a second semicircular piston segment in the other of said grooves, means for maintaining said piston segments against rotation with said rotor while permitting lateral oscillation of said segments, an inlet recess and a discharge recess within said housing adjacent said spherical surface of said rotor communicating with each of said grooves, both of said recesses extending transversely with respect to said grooves, said recesses being circumferentially spaced from each other and being disposed on opposite sides of a plane extending between the ends of said segments and along the axis of said rotor, said first segment blocking said other of said grooves at one of said intersections of said grooves and simultaneously effecting compression fluid in said one of said grooves against said second segment, said second segment blocking said one of said grooves at the other of said intersections of said grooves and simultaneously effecting compression fluid in said other of said grooves against said first segment.

10. A pump comprising a housing having a spherical chamber therein, a rotor within said chamber, said rotor having a spherical surface arranged to engage the surface of said chamber, said rotor having a pair of circumferential grooves formed in said spherical surface of said rotor, said grooves intersecting each other at two diametrically opposite points, a first semicircular piston segment in one of said grooves, a second semicircular piston segment in the other of said grooves, means for maintaining said piston segments against rotation with said rotor while permitting lateral oscillation of said segments, and two diametrically opposite inlet recesses and two diametrically opposite discharge recesses within said housing adjacent said spherical surface of said rotor, one of said inlet recesses and one of said discharge recesses communicating with each of said grooves, all of said recesses extending transversely with respect to said grooves, each of said inlet recesses being circumferentially spaced from the corresponding one of said discharge re-

cesses and being disposed on the opposite side from said corresponding one of said discharge recesses with respect to a plane extending between the ends of said segments and along the axis of said rotor, said first segment extending across the other of said grooves and dividing said other of said grooves into a first portion communicating with one of said inlet recesses and a second portion communicating with one of said discharge recesses, said second segment extending across said one of said grooves and dividing said one of said grooves into a first portion communicating with the other of said inlet recesses and a second portion communicating with the other of said discharge recesses, rotation of said rotor causing relative movement of said segments to effect an increase in size of said first portions and a simultaneous reduction in size of said second portions whereby simultaneous intake and discharge of fluid is effected to and from each of said grooves.

11. A pump comprising a housing having a spherical chamber therein, a rotor within said chamber, said rotor having a spherical surface arranged to engage the surface of said chamber, said rotor having a pair of circumferential grooves formed in said spherical surface of said rotor, said grooves intersecting each other at two diametrically opposite points, a first semicircular piston segment in one of said grooves, a second semicircular piston segment in the other of said grooves, means for maintaining said piston segments against rotation with said rotor while permitting lateral oscillation of said segments, and two diametrically opposite inlet recesses and two diametrically opposite discharge recesses within said housing adjacent said spherical surface of said rotor, one of said inlet recesses and one of said discharge recesses communicating with each of said grooves, each of said inlet recesses being circumferentially spaced from the corresponding one of said discharge recesses and being disposed on the opposite side from said corresponding one of said discharge recesses with respect to a plane extending between the ends of said segments and along the axis of said rotor, said first segment extending across the other of said grooves and dividing said other of said grooves into a first portion communicating with one of said inlet recesses and a second portion communicating with one of said discharge recesses, said second segment extending across said one of said grooves and dividing said one of said grooves into a first portion communicating with the other of said inlet recesses and a second portion communicating with the other of said discharge recesses, rotation of said rotor causing relative movement of said segments to effect an increase in size of said first portions and a simultaneous reduction in size of said second portions whereby simultaneous intake and discharge of fluid is effected to and from each of said grooves, said rotor effecting change in size of said first and second portions to a maximum and a minimum respectively during each half revolution whereby intake and discharge of fluid to and from each groove is effected twice per revolution of said rotor.

12. A pump comprising a housing having a spherical chamber therein, a rotor within said chamber, said rotor having a spherical surface arranged to engage the surface of said chamber, said rotor having a pair of circumferential grooves formed in said spherical surface of said rotor, said grooves intersecting each other at two

diametrically opposite points, a first semicircular piston segment in one of said grooves, a second semicircular piston segment in the other of said grooves, means for maintaining said piston segments against rotation with said rotor while permitting lateral oscillation of said segments, and two diametrically opposite inlet recesses and two diametrically opposite discharge recesses within said housing adjacent said spherical surface of said rotor, one of said inlet recesses and one of said discharge recesses communicating with each of said grooves, each of said inlet recesses being circumferentially spaced from the corresponding one of said discharge recesses and being disposed on the opposite side from said corresponding one of said discharge recesses with respect to a plane extending between the ends of said segments and along the axis of said rotor, said first segment extending across the other of said grooves and dividing said other of said grooves into a first portion communicating with one of said inlet recesses and a second portion communicating with one of said discharge recesses, said second segment extending across said one of said grooves and dividing said one of said grooves into a first portion communicating with the other of said inlet recesses and a second portion communicating with the other of said discharge recesses, one side of each of said segments being disposed toward the portion of each of said grooves communicating with one of said inlet recesses and the other side of each of said segments being disposed toward the portion of each of said grooves communicating with a discharge recess during one half revolution of said rotor, said one side of each of said segments being disposed toward the portion of each of said grooves communicating with a discharge recess and said other side of each of said segments being disposed toward the portion of each of said grooves communicating with an inlet recess during the next half revolution of said rotor.

13. A pump comprising a housing having a spherical chamber therein, a rotor within said chamber, said rotor having a truncated spherical surface arranged to engage the surface of said chamber, said rotor having its axis of rotation perpendicular to the faces of the truncated portions thereof, said rotor having a pair of circumferential grooves formed in said spherical surface of said rotor, said grooves intersecting each other at two diametrically opposite points, said grooves being inclined at equal angles with respect to a plane perpendicular to the axis of rotation of said rotor and extending through the intersections of said grooves, a semicircular piston segment positioned in each of said grooves, means for maintaining said piston segments against rotation with said rotor while permitting lateral oscillation of said segments, and an inlet recess and a discharge recess within said housing adjacent said spherical surface of said rotor communicating with each of said grooves, both of said recesses extending transversely with respect to said grooves, said recesses being circumferentially spaced from each other and being disposed on opposite sides of a plane extending between the ends of said segments and along the axis of said rotor.

14. A pump comprising a housing having a spherical chamber therein, a rotor within said chamber, said rotor having a truncated spherical surface arranged to engage the surface of said chamber, said rotor having its axis of rotation perpendicular to the faces of the truncated por-

tions thereof, means engaging said housing and the face of at least one of said truncated portions of said rotor to prevent oscillation of the axis of rotation of said rotor, said rotor having a pair of circumferential grooves formed in said spherical surface of said rotor, said grooves intersecting each other at two diametrically opposite points, said grooves being inclined at equal angles with respect to a plane perpendicular to the axis of rotation of said rotor and extending through the intersections of said grooves, a semicircular piston segment positioned in each of said grooves, means for maintaining said piston segments against rotation with said rotor while permitting lateral oscillation of said segments, and an inlet recess and a discharge recess within said housing adjacent said spherical surface of said rotor communicating with each of said grooves, both of said recesses extending transversely with respect to said grooves, said recesses being circumferentially spaced from each other and being disposed on opposite sides of a plane extending between the ends of said segments and along the axis of said rotor.

15. A pump comprising a housing having a spherical chamber therein, a rotor within said chamber, said rotor having a spherical surface arranged to engage the surface of said chamber, said rotor having a pair of spherical grooves formed in said spherical surface of said rotor, said grooves intersecting each other at two diametrically opposite points, said grooves being inclined at equal angles with respect to a plane perpendicular to the axis of rotation of said rotor and extending through the intersections of said grooves, a semicircular piston segment positioned in each of said grooves, means for maintaining said segments against rotation with said rotor while permitting lateral oscillation of said segments, and a pair of inlet recesses and a pair of discharge recesses within said housing adjacent said spherical surface of said rotor, all of said recesses extending transversely with respect to said grooves, each of said inlet recesses being circumferentially spaced from the corresponding one of said discharge recesses and being disposed on the opposite side from said corresponding one of said discharge recesses with respect to a plane extending between the ends of said segments and along the axis of said rotor, one of said inlet recesses and one of said discharge recesses communicating with each of said grooves, each of said recesses being of sufficient length to communicate with its respective groove throughout each revolution of said rotor.

16. A pump comprising a housing having a spherical chamber therein, a rotor within said chamber, said rotor having a spherical surface arranged to engage the surface of said chamber, said rotor having a pair of circumferential grooves formed in said spherical surface thereof, said grooves intersecting each other at two diametrically opposite points, a semicircular piston segment positioned in each of said grooves, said housing having two key-receiving recesses therein adjacent said spherical surface of said rotor and extending transversely with respect to said grooves, two keys arranged for lateral oscillation within said housing, one of said keys being slideable in each of said key-receiving recesses, a pin for pivotally connecting each of said keys to one of said segments to prevent rotation of said segments with said rotor, and an inlet recess and a discharge recess within said housing adjacent said spherical surface of said rotor communi-

cating with each of said grooves, both of said last-named recesses extending transversely with respect to said grooves, said last-named recesses being circumferentially spaced from each other and being disposed on opposite sides of a plane extending between the ends of said segments and along the axis of said rotor.

17. A pump comprising a housing having a spherical chamber therein, a rotor within said chamber, said rotor having a spherical surface arranged to engage the surface of said chamber, said rotor having a pair of circumferential grooves formed in said spherical surface thereof, said grooves intersecting each other at two diametrically opposite points, a semicircular piston segment positioned in each of said grooves, said housing having two diametrically opposite key-receiving recesses therein adjacent said spherical surface of said rotor and extending transversely with respect to said grooves, two diametrically opposite keys arranged for lateral oscillation within said housing, one of said keys being slideable in each of said key-receiving recesses, a pin for pivotally connecting each of said keys to a corresponding one of said segments to prevent rotation of said segments with said rotor, each of said pins engaging its corresponding key and corresponding segment substantially at the center of said corresponding key and said corresponding segment, and an inlet recess and a discharge recess within said housing adjacent said spherical surface of said rotor communicating with each of said grooves, both of said last-named recesses extending transversely with respect to said grooves, said last-named recesses being circumferentially spaced from each other and being disposed on opposite sides of a plane extending between the ends of said segments and along the axis of said rotor.

18. A pump comprising a housing having a spherical chamber therein, a rotor within said chamber, said rotor having a spherical surface arranged to engage the surface of said chamber, said rotor having a pair of circumferential grooves formed in said spherical surface thereof, said grooves intersecting each other at two diametrically opposite points, a semicircular piston segment positioned in each of said grooves, the bottom of each of said grooves having a spherical surface concentric with the surface of said rotor, the inner surface of each of said piston segments having a curvature corresponding to that of its respective groove, means for maintaining said piston segments against rotation with said rotor while permitting lateral oscillation of said segments thereof, and an inlet recess and a discharge recess within said housing adjacent said spherical surface of said rotor communicating with each of said grooves, both of said recesses extending transversely with respect to said grooves, said recesses being circumferentially spaced from each other and being disposed on opposite sides of a plane extending between the ends of said segments and along the axis of said rotor.

19. A pump comprising a housing having a spherical chamber therein, a rotor within said chamber, said rotor having a spherical surface arranged to contact the surface of said chamber, said rotor having a pair of circumferential grooves formed in said spherical surface thereof, said grooves intersecting each other at two diametrically opposite points, a semicircular piston segment positioned in each of said grooves, two

diametrically opposite inlet recesses within said housing, one of said inlet recesses communicating with each of said grooves, two diametrically opposite discharge recesses within said housing, one of said discharge recesses communicating with each of said grooves, all of said recesses extending transversely with respect to said grooves, each of said inlet recesses being spaced circumferentially from a corresponding one of said discharge recesses, and means maintaining said piston segments against rotation with said rotor while permitting lateral oscillation of said segments, said means maintaining one pair of adjacent ends of said segments in the space between one of said transverse inlet recesses and the corresponding one of said discharge recesses, said means maintaining the other pair of adjacent ends of said segments in the space between the other of said inlet recesses and the other of said discharge recesses, one of said segments having one end extending beyond said one of said inlet recesses and its other end extending beyond said other of said discharge recesses to block communication between said last-named recesses and one of said grooves, the other of said segments having one end extending beyond said other of said inlet recesses and its other end extending beyond said one of said discharge recesses to block communication between said last-named recesses and the other of said grooves.

20. A pump comprising a housing having a spherical chamber therein, a rotor within said chamber, said rotor having a spherical surface arranged to engage the surface of said chamber, said rotor having a pair of circumferential grooves formed in the spherical surface thereof, said grooves intersecting each other at diametrically opposite points, a first piston segment positioned in one of said grooves and extending substantially half the length of said one of said grooves, a second piston segment positioned in the other of said grooves and extending substantially half the length of said other of said grooves, means for maintaining said piston segments against rotation with said rotor while permitting lateral oscillation of said segments, two diametrically opposite inlet recesses within said housing adjacent said spherical surface of said rotor, and two diametrically opposite discharge recesses within said housing adjacent said spherical surface of said rotor, all of said recesses extending transversely with respect to said grooves, each of said inlet recesses being circumferentially spaced from the corresponding one of said discharge recesses and being disposed on the opposite side from said corresponding one of said discharge recesses with respect to a plane extending between the ends of said segments and along the axis of said rotor, one of said inlet recesses and one of said discharge recesses communicating with each of said grooves, said one of said grooves being in communication with one of said inlet recesses adjacent one end of said second segment and being in communication with one of said discharge recesses adjacent the other end of said second segment, said other of said grooves being in communication with the other of said inlet recesses adjacent one end of said first segment and being in communication with the other of said discharge recesses adjacent the other end of said first segment.

FLOYD M. KIRKPATRICK.
